UNITED STATES PATENT OFFICE.

ELISHA C. MATHEWS, OF JACKSONVILLE, ILLINOIS.

BASE FOR SWITCH-STANDS, &c.

SPECIFICATION forming part of Letters Patent No. 610,684, dated September 13, 1898.

Application filed February 7, 1898. Serial No. 669,401. (No model.)

To all whom it may concern:

Be it known that I, ELISHA C. MATHEWS, a citizen of the United States, residing at Jacksonville, in the county of Morgan and 5 State of Illinois, have invented new and useful Improvements in Bases for Switch-Stands, &c., of which the following is a specification.

My invention is an improved base for the signaling apparatus employed in interlocking 10 switches, railroad-crossings, switch-stands, fence-posts, and other places where a firm and strong foundation or pier is needed; and it consists in certain novel features hereinafter described and claimed.

15 In the accompanying drawings, which fully illustrate my invention, Figure 1 is a side elevation of a foundation or base constructed in accordance with my improvements. Fig. 2 is a vertical diametrical section of the same. 20 Fig. 3 is a plan view of the same, and Figs. 4 and 5 are detail views.

In carrying out my invention I employ a cylindrical pipe or tile A, which is set on end and is provided at its lower end with the internal shoulders B. Bearing against these shoulders is a cross-bar or tie C, having a rib D on its upper side to prevent buckling and constructed with the grooves E at its ends, having overhanging lips F. Fitted in these 30 transverse grooves and held by the lips are bolts G, which extend upward to the top of the tile and pass through the cap-plate H. This cap-plate fits on the top of the tile and is provided on its under side with the ribs I, which prevent buckling of the plate and hold 35 it in place by engaging notches J in the upper end of the tile. Nuts K are fitted on the upper extremities of the bolts and are turned home against the cap-plate to bind the same 40 firmly upon the tile. On the upper side of the cap are the parallel ribs L, having inwardly-projecting flanges M at their upper edges as clearly shown. In the drawings I have shown one of the levers of a switch signaling apparatus mounted on the cap-plate by means of a bracket, which is secured by 45 bolts held under the flanges M, but it will be readily understood that a fence-post, a switch-lever, or any similar device may be so fastened 50 and secured in place.

In placing my device in its operative position the tie or cross-bar C is placed against the shoulders B, and the bolts G are moved laterally, so that their heads will engage under the lips F, after which a small board is placed 55 on the upper end of the tile and the nuts K tightened. The device is then inserted in the excavation prepared for it and the earth tamped solidly around it and forced under the cross-bar or tie. The wooden cover is then 60 removed and earth tamped within the tile, so as to hold the bolts in their proper positions and effect a thorough burial of the tile. The cap-plate is then fitted in place and the nuts K turned home against the same. The se- 65 curing-bolts to hold the fence-post or other device are then inverted, so that their heads may engage the flanges M and be slipped into place, as will be readily understood.

It will be seen from the foregoing descrip- 70 tion, taken in connection with the accom- 75 panying drawings, that I have provided a de- 80 vice which furnishes a firm and strong foun- 85 dation or pier which can be easily fitted together in its operative position at a slight 90 cost and which is free of all unnecessary joints. The overhanging lips and flanges facilitate the fitting together of the bolts and the parts held by them. The tile or founda- 95 tion-pipe is preferably circular in cross-sec- 100 tion, but may be of any desired shape, and it may sometimes be desirable to employ an angular shape in order to guard against turning of the pipe in the ground.

Having thus described my invention, what 85 I claim, and desire to secure by Letters Pat- 105 ent, is—

1. The combination of a tile or pipe, having internal shoulders at its lower end, a cross-bar fitting against said shoulders and pro- 90 vided at its ends with transverse grooves hav- 95 ing overhanging lips, bolts having their heads fitted in said grooves and under said lips and extending up to the upper end of the pipe, a cap-plate on the upper end of the tile held by 95 said bolts, and means carried by the cap-plate for holding a fence-post or other device.

2. The combination of a tile or pipe having notches in its upper end, a cap-plate having ribs engaging said notches, and bolts held in 100

the lower end of the tile and securing the said cap-plate.

3. The combination with a tile or pipe, of a cap fitted on the upper end of the same and provided on its upper sides with parallel ribs having horizontal flanges at their upper edges, and means for securing the cap rigidly to the pipe.
- 5

In testimony whereof I have hereunto set my hand in the presence of two subscribing witnesses.

ELISHA C. MATHEWS.
